UNITED STATES PATENT OFFICE

144,157

DESIGN FOR A THUMBPICE FOR A DRAWER LATCH OR SIMILAR ARTICLE

Herbert C. Dahl, Columbus, Pa., assignor to Corry-Jamestown Manufacturing Corporation, Corry, Pa., a corporation of New York

Application March 17, 1945, Serial No. 118,540

Term of patent 7 years

(Cl. D50—5)

To all whom it may concern:

Be it known that I, Herbert C. Dahl, a citizen of the United States, residing at Columbus, in the county of Warren and State of Pennsylvania, have invented a new, original, and ornamental Design for a Thumpiece for a Drawer Latch or Similar Article, of which the following is a specification, reference being had to the accompanying drawing, forming part thereof, and in which

Fig. 1 is a front elevational view of a thumbpiece for a drawer latch or similar article, showing my new design;

Fig. 2 is a side elevational view;
Fig. 3 is a bottom plan view;
Fig. 4 is an end view taken substantially as indicated at 4—4 of Fig. 2; and

Fig. 5 is a further end view taken substantially as indicated at 5—5 of Fig. 2.

I claim:

The ornamental design for a thumbpiece for a drawer latch or similar article, substantially as shown.

HERBERT C. DAHL.
